UNITED STATES PATENT OFFICE.

ARTHUR ROBERT KRAUSE, OF WOODHAVEN, NEW YORK, ASSIGNOR TO LION ELECTRIC MANUFACTURING CO., INC., A CORPORATION OF NEW YORK.

DESIGN FOR A LAMP WALL BRACKET.

Application filed October 7, 1924. Serial No. 10,989. Term of patent 7 years.

To all whom it may concern:

Be it known that I, ARTHUR ROBERT KRAUSE, a citizen of the United States, residing at 3966 Fulton Street, Woodhaven, Long Island, county of Queens, and State of New York, have invented a new, original, and ornamental Design for a Lamp Wall Bracket, of which the following is a specification, reference being had to the accompanying drawing, which forms a part of this application and illustrates my design applied to a lamp wall bracket.

In the drawing, Figure 1 is a front eleva-

tion and Figure 2 is a side elevation of the bracket positioned as in use.

I claim:—

The ornamental design for a lamp wall bracket, as shown.

ARTHUR ROBERT KRAUSE.
